UNITED STATES PATENT OFFICE.

JOHN W. LANE, OF PORTLAND, MAINE.

RICE HULLING AND CLEANING MACHINE.

SPECIFICATION forming part of Letters Patent No. 291,362, dated January 1, 1884.

Application filed October 9, 1883. (No model.)

To all whom it may concern:

Be it known that I, JOHN W. LANE, a citizen of the United States, residing at Portland, in the county of Cumberland and State of Maine, have invented certain new and useful Improvements in Rice-Hulling and Cleaning Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a perspective view of my improved rice huller and cleaner without the frame. Fig. 2 is a perspective view of the huller and cleaner with the frame, the exhaust-fan and its pipe omitted. Fig. 3 is a vertical central-
20 section taken longitudinally through the rice huller and cleaner and its driving mechanism, also showing the exhaust pipe and fan. Fig. 4 is a cross-section through the huller and cleaner in the plane indicated by dotted lines
25 $\pi\pi$ on Fig. 3.

This invention relates to machinery for hulling and cleaning rice; and it consists in certain novel constructions and combinations of devices, which will be fully understood from
30 the following description, when taken in connection with the annexed drawings and claims.

A represents a cylinder, about six feet long and about thirty inches in diameter, provided with projections on ribs a on the inside, as shown. On the outside of this cylinder A there is a gear, b , around it at one end, as shown clearly in Fig. 1, which is driven by a pinion, b' . It also has two rings, $H H$, near its ends, adapted to run in grooves of the
35 wheels $C C$, on both sides of and beneath the cylinder A, on which the latter is supported and revolves. These wheels prevent endwise movement of the cylinder, and the bearings of said wheels are mounted on a suitable base,
40 F, of the main frame. The cylinder A is held down in place on wheels $C C$ by means of grooved wheels $d d$ and rod G, fixed to the stationary heads $A' A^2$ of the cylinder. There is a perforated cylinder, B, inside of the cylinder A, and of the same length, which is mounted upon a shaft, B', having spiders u at its ends, and at intermediate points between

its ends, to which said cylinder B is fastened, as shown in Fig. 3. The projections or ribs a , on the exterior of the cylinder B, I call 55 "wipers," and their purpose is to impart blows to the rice. They are beveled, so as to give draw-strokes and direct the rice tangentially outward against the beveled ribs a on the outer cylinder, A, and they are numer- 60 ously perforated, to present roughened edges. The shaft B', inside of the cylinder B, extends a sufficient distance beyond its end to receive a driving-pulley, R, which is belted, to receive motion from any suitable prime motor.

At the ends of the cylinders A B are the cast-iron heads $A' A^2$, above referred to, fitted 65 against said ends, so that the cylinder will run rice-tight thereat. The shaft B' is journaled in the boxes of the heads $A' A^2$, and also 70 in a box upon the end of a stand, L, resting upon the floor, as shown in Fig. 3. One of the heads, A' , has a hopper, J, for feeding the rice into the space between the inner and outer cylinders, A and B. In this hopper is a valve, 75 J' , for regulating the supply or feed. On the same head is an opening, which communicates with a pipe, S, and the space between the two cylinders, (shown in Fig. 3,) leading to an exhausting engine or fan, V, driven from the 80 large pulley by means of a belt, v. By these means the dust, &c., is drawn from the cylinders A B as the rice is cleaned.

In Fig. 2 I show the train of gears by which motion and proper speed are communicated 85 to the outside cylinder from the main shaft B' through the medium of pinion-wheels $b^3 b^4$. Through the head A^2 is a passage, T, for the escape of the hulled and cleaned rice, which discharge is regulated by a valve, t.

Figs. 1 and 2 show the pinion b' , which engages with the gear b , and rotates the large cylinder A, which pinion is keyed on the shaft of a large spur-wheel, b^2 , that receives motion from the main shaft B'.

Through the heads $A' A^2$ are openings W, for the free admission of air to the interior of the machine, so that by the action of the exhaust-fan V currents of air will be drawn through the cylinders, and remove the dust, 90 &c., from the rice during the hulling process.

What I claim, and desire to secure by Letters Patent, is—

1. In a rice hulling and cleaning machine,

the combination of the rotary imperforate cylinder A, having a discharge-passage, T, and internal beveled ribs, a, the perforate rotary cylinder B, provided with external wipers, a', 5 beveled and perforated, a feed-passage for the rice, and a suction-fan, communicating with the space between the two cylinders, substantially as described.

2. In a rice hulling and cleaning machine, 10 the combination of the internal perforate rotating cylinder having the perforated and beveled wipers, the external imperforate rotating cylinder having internal beveled ribs, the stationary heads for both cylinders, provided with feed and discharge passages for the 15 rice, and an air-exhausting device, substantially as described.

3. The combination of an exterior cylinder having a positive rotation, and an interior perforate cylinder geared thereto, and having perforated beveled wipers on the exterior thereof, 20 substantially as described.

4. The combination of a rotary external im-

perforate cylinder having ribs on the interior thereof, a rotary perforate cylinder having perforated and beveled wipers on the exterior thereof, fixed heads A' A², provided with air-inlets and feed and discharge passages for the rice, and means for inducing blasts of air through the cylinders, substantially as described.

5. The combination of the external rotary cylinder, A, provided with bands, the grooved wheels, and stationary heads, with the internal perforate cylinder, B, provided with perforate wipers a', the spiders and main shaft, 35 gears for driving both cylinders from said shaft, and means for inducing a blast of air through the cylinders, substantially as described.

In testimony whereof I affix my signature in presence of two witnesses.

JOHN W. LANE.

Witnesses:

W. H. McDONALD,

WILLIAM BURROWES.
